Gene Moyer, Royersford, Pa., assignor to West Disinfecting Company, Long Island City, N. Y., a corporation of New York

Application November 25, 1953, Serial No. 27,782

Term of patent 14 years

(Cl. D58—6)

To all whom it may concern:

Be it known that I, Gene Moyer, a citizen of the United States, residing in Royersford, Montgomery County, Pennsylvania, have invented a new, original, and ornamental Design for a Bottle, of which the following is a specification, reference being had to the accompanying drawing, forming a part thereof, in which:

Figure 1 is a perspective view of the bottle, embodying my new design;

Figure 2 is a side elevational view thereof;

Figure 3 is a plan view thereof;

Figure 4 is a rear elevational view thereof;

Figure 5 is a front elevational view thereof; and

Figure 6 is a bottom view thereof.

I claim:

The ornamental design for a bottle, as shown.
